CLAIM

The ornamental design for a baby carriage, as shown and described.

DESCRIPTION

FIG. 1 is a perspective view of a baby carriage showing our new design, the carrier being removed from the baby carriage for clarity of illustration;

FIG. 2 is a rear perspective view thereof;

FIG. 3 is a front perspective view thereof;

FIG. 4 is a rear perspective view thereof with the baby carriage in an inclined, rearward facing position;

FIG. 5 is a front perspective view thereof, showing the carriage in an inclined, forward facing position with carrier's hood folded and a torso guard attached;

FIG. 6 is a front perspective view thereof as shown in FIG. 5 but with the open hood and the torso guard removed; and

FIG. 7 is a bottom plan view of the carrier, the carrier is shown separately for clarity of illustration.

*FIG. 1.**FIG. 2.*FIG. 5.

FIG. 4.

FIG. 3.

FIG. 6.**FIG. 7.**
